UNITED STATES PATENT OFFICE.

PHILIP HINKLE, OF SAN FRANCISCO, CALIFORNIA.

GRINDING-PAN.

SPECIFICATION forming part of Letters Patent No. 400,681, dated April 2, 1889.

Application filed November 16, 1888. Serial No. 291,036. (No model.)

To all whom it may concern:

Be it known that I, PHILIP HINKLE, of the city and county of San Francisco, State of California, have invented an Improvement in 5 Grinding-Pans; and I hereby declare the following to be a full, clear, and exact description of the same.

My invention relates to certain improvements in grinding-pans; and it consists in 10 certain details of construction, which will be more fully explained by reference to the accompanying drawings, in which—

Figure 1 is a vertical section taken centrally across the pan. Fig. 2 is a plan view with the 15 top of the pan removed, showing part of the revolving grinding-rollers also removed. Fig. 3 is a vertical section through one of the rollers and one of the lifting-plates. Fig. 4 is a detail view of the bottom of one of the rollers, showing the manner of fastening the ring-shoes on same.

A is the pan-bottom, which is preferably cast with low flaring sides B, within which is 20 fitted a similarly-shaped flaring ring-die, C, which is fixed into place by calking between it and the sides of the pan, as shown at D. The inner portion of the bottom is made concave from below, and in the center is a conically-shaped hollow sleeve or casing, E, 25 through which the vertical driving-shaft F extends. To the lower end of this shaft is secured the bevel-gear G, and this gear is set well up into the concavity of the bottom of the pan, which enables me to set the pan much 30 lower than would otherwise be the case.

H is a beveled driving gear-wheel fixed to a horizontal shaft, I, and this gear engages with the gear G and drives the vertical shaft. To 35 the upper end of this shaft is fixed a carrier, J, which extends down outside the hollow shaft-casing E, and is thence inclined outwardly, so as to correspond with the inclined bottom of the pan. The inclination of the upper surface of the pan-bottom and of this carrier is such that they stand at right angles with the sides of the pan-bottom and with the face of the ring-die C, which is fixed around its periphery.

The carrier J has radial slots K formed in it, 40 which act as guides for the slides L, which are

fitted into these slots so as to move to or from the center, as required. These slides serve to support the shafts M, which are fixed in them, and extend upwardly at right angles with the slides and with the inclined bottom of the pan. 55 Upon the tops of the guides are fixed wrought-iron or steel plates K', which steady the slides L and hold them in place, and also prevent them from being clogged.

Upon the shafts M are fitted the grinding-rollers O, so as to turn upon the shafts. These rollers have ring-shoes P fixed upon their peripheries, being calked, as described, for the dies within the pan. The faces of these rollers and their shoes stand parallel with the 60 inner face of the ring-die C, so that when they are driven around by the movement of the carrier J they will roll against the die C. These slides L, traveling in the radial guides K, allow the rollers to move to and from the 65 center, and thus accommodate themselves to the character and quantity of the material which may lie between them and the die C, where the grinding or pulverizing takes place.

The lower edges of the rings or shoes P are 70 fitted to the bottoms of the rollers O by the dovetailed slots and keys, as shown at Q, Fig. 4. This serves to keep them in place. The central portion of the lower surface of the rollers O is made with a concave chamber, S, which fits over the correspondingly-shaped convex portion S' of the slides upon 75 which the rollers are journaled, and steel rings T are fixed one upon the top of the cone and the other upon the interior of the depression in the bottom of the roller, as shown in Fig. 1. Between these two rings one or 80 more rings, U, are loosely fitted, so that the movement caused by the rotation of the rollers will be considerably relieved from friction and the bottom of the rollers kept out 85 of contact with the surface beneath.

Upon the upper end of each of the roller-shafts is fitted a washer, V, and the upper ends of the shaft being screw-threaded the 90 nut W screws down upon this washer. The central portion of each of the rollers O is extended upward in the form of a sleeve, which surrounds the shaft, on the upper end of which the washer V rests and against which 95 100

the sleeve turns. This prevents the roller from being forced upward on this shaft by its movement in traveling around in contact with the die C within the pan.

5 When it is necessary to remove the rollers for any purpose, it is done by unscrewing the nut W, and by means of the rings or handles shown at X the rollers may be lifted off their shafts when the top of the pan and the connecting parts have been removed.

Around the upper part of the carrier J is fitted a tank or reservoir, Y, into which clear water is led through the pipes Z. From the lower part of this reservoir inclined tubes a 15 extend outwardly toward the upper end of each of the roller-shafts M. These shafts M are made hollow, and conduits b have their outer ends bent so as to enter the upper ends of these shafts, into which they are fitted.

20 The inner ends of these conduits slide telescopically within the pipes a, and this sliding allows them to adjust themselves to the radial movements of the rollers as they rotate around the pan. Through these pipes and 25 conduits a b and through the hollow shaft M water passes from the reservoir, and passing below the slides L it serves to wash out any grit or dirt and to act as a lubricant, so that these parts will move easily upon each other.

30 The lower ends of the slides fit closely around the carrier; but the inner part is raised a little, so that the water can flow toward the center beneath the slide, and it returns to the outer end through slots K², made on top of 35 the slides and beneath the plates K', as shown in Fig. 3. Other conduits, c, extend from the bottom of the reservoir down inside of the vertical portion of the carrier J and between it and the shaft-casing, which stands up in 40 the center of the pan, and the water passes through these conduits down around the shaft-casing E and beneath the bottom of the carrier J, between it and the inclined bottom of the pan, and flowing constantly outward 45 prevents any accumulation of the material, which would cause undue friction or prevent the free motion of the carrier.

The pan is supported upon the hollow legs d, which are secured to it by bolts e, the legs 50 being removable, so as to reduce the whole to a small compass for transportation. The top f of the pan is formed with flanges, so they may be bolted upon the corresponding flanges at the top of the inclined sides of the pan; 55 bottom, as shown plainly in Fig. 1, and a tight joint is made by means of a rubber or other packing-ring, as shown at g.

h is the feed-opening by which the charge is introduced into the pan. 60 i is a series of inclined steel plates which are fixed to the outer edges of the carrier J, and they travel along upon the bottom of the pan between the rollers, so that when the carrier is rotating and the rollers traveling 65 around in contact with the ring-die C on the interior of the pan these plates, moving over

the bottom of the pan, lift up any material which may be settled there, and discharging it in an upwardly-inclined direction from the rear end of the plates i it passes directly 70 between the following roller and the die at a point about midway between the top and bottom of the periphery of the roller, so that the material is constantly lifted up into position to be ground or pulverized between the rollers and the die. When the material is sufficiently pulverized, it is discharged through a suitable screen, j, and is conveyed into the inclined sluices k, with amalgamated plates 80 in the bottom, upon which to save fine gold or amalgam. From these sluices the material is delivered into a shaking concentrator, m, supported upon spring-arms n, and caused to oscillate by means of rods o from eccentrics or cranks p on the shaft I, so as to work in 85 unison with the pan.

Whenever the ring-shoes upon the rollers become worn, so as to be materially lighter, I compensate this by placing supplemental weights r upon the tops of the rollers, the 90 weights having central holes, so as to fit around the upwardly-extending central portion of the rollers.

This construction also enables me to make a low compact pan which is easily separated 95 into comparatively small portions for shipment.

Having thus described my invention, what I claim as new, and desire to secure by Letters Patent, is—

1. In a grinding-pan, the inclined bottom, the outwardly-inclined sides, with the correspondingly-shaped ring-die fixed therein by calking, the carrier or driver, the bottom of which is inclined to correspond with the bottom of the pan, and having the radial guide-slots, in combination with guides fitted in said slots, the top plates, the upwardly-extending shafts fixed in said guides so as to extend at an inclination outwardly, and the 105 rollers turning upon said shafts, with their peripheries traveling in contact with the ring-die, substantially as herein described.

2. A grinding-pan having the inclined bottom and sides, the correspondingly-inclined die, the rotary carrier having radial slots in its outer periphery, with top plates and guides movable in said slots, said guides having upwardly-projecting cones or hubs, and the inclined shafts M, fixed in said cones or hubs, 115 in combination with rollers fitting said shafts, having upwardly-extending sleeves from the top, and concavities in the bottom fitting the conical hubs of the guides, and the anti-frictional rings T and U, the holding nut and 120 washer at the top of the shaft, substantially as herein described.

3. In a grinding-pan, the inclined bottom and sides, the correspondingly-inclined rollers, the inclined shafts, and the radially-moving 125 guides, in combination with a central rotating reservoir, and pipes connecting said reser-

voir with the upper ends of the shafts, so as to discharge water through them and beneath the rollers and guides, substantially as herein described.

5. 4. In a grinding-pan, the inclined bottom and sides, the radially-moving guides, the inclined shafts, the grinding-rollers journaled at the corresponding inclination upon said shafts, the conduits, and pipes, whereby water

is discharged through the roller-shafts and 10 between the carrier and the pan-bottom, substantially as herein described.

In witness whereof I have hereunto set my hand.

PHILIP HINKLE.
